UNITED STATES PATENT OFFICE

EARL T. BENNINGTON, OF CLEVELAND HEIGHTS, OHIO, ASSIGNOR TO THE CLEVELAND CRANE AND ENGINEERING COMPANY, OF WICKLIFFE, OHIO, A CORPORATION OF OHIO

TESTING APPARATUS

Application filed May 18, 1926. Serial No. 108,991.

This invention relates to a traveling carrier designed to convey hollow bodies and to supply fluid to the interior thereof for testing or other purposes, and more particularly to a carrier adapted for testing hollow bodies for leaks by supplying fluid under pressure to the interior thereof. The invention, as disclosed herein, is applied to the testing of radiator sections as they come from the molds.

It is an object of the present invention to provide a carrier which is adapted to convey the hollow articles and which has article supporting and fluid conducting means associated therewith through which communication may be established between the interior of the hollow article and fluid conducting means mounted independently of the carrier.

A further object of the invention is to provide a carrier of the character above referred to which is simple in construction, effective in operation and inexpensive.

With the above and other objects in view, the invention may be said to comprise the device as illustrated in the accompanying drawings hereinafter described and particularly set forth in the appended claims together with such variations and modifications thereof as will be apparent to one skilled in the art to which the invention apertains.

Reference should be had to the accompanying drawings, forming a part of this specification in which:

Fig. 1 is a side elevation of the carrier with a row of radiator sections suspended therefrom;

Fig. 2 is an end elevation of the loaded carrier; and

Fig. 3 is a vertical section through one of the radiator sections, showing the supporting clamp engaging the upper end of the section and the sealing clamp in place on the lower end thereof.

Referring to the accompanying drawings, there is shown a section of an overhead monorail trackway 1 upon which the supporting wheels 2 of the carriers travel. This trackway will extend from the casting room or from any other point from which the articles

to be tested are obtained and extend past the testing station and to a storage room or other point to which the tested articles are to be taken. The carrier is designed to permit testing of the articles without removing them from the carrier so that no additional handling of the articles is required in connection with the testing operation. The carrier is suspended from the supporting wheels 2 by means of wheel frames 3 connecting the axles

of the supporting wheels to carrier cross-bars 4 which extend across the space between the opposite sides of the main frame member 5 intermediate the ends thereof. The frame member 5 is a hollow tubular member forming the sides and ends of the carrier frame and this tubular member is provided, adjacent one end of the carrier, with an inlet 6 which is provided with a tubular coupling member 7 which is adapted to be

attached to a hose extending from a water main so that water under pressure may be admitted to the interior of the tubular frame member 5. Along the opposite sides of the carrier frame, the tubular member 5 is provided with spaced downwardly projecting nipples 8 to which are connected the upper ends of flexible tubular suspension members 9, which are preferably sections of flexible hose.

A valve 10 is provided in each nipple 8 so that communication between any tubular member 9 and the tubular frame member can be cut off when desired.

Article supporting clamps are attached to the lower ends of the suspension members 9 and each of these clamps consists of jaws 11 and 12 between which the hollow article to be tested is clamped. The jaw 11 is connected to the suspension member 9 and the jaw 12 is supported upon the jaw 11 by means of a pin 13 which is carried by a lug 14 projecting downwardly from the upper portion of the jaw 11. The jaw 11, adjacent its lower end, is provided with a pin 15 which is adapted to project through an opening to the interior of the article held by the clamp and this pin has an axial bore 16 at its outer end which is threaded to receive a clamping bolt 17 which extends through the jaw 12.

The particular clamp, shown herein, is designed for supporting a radiator section and this radiator section is designated 18 in the drawing.

5 The radiator section is provided, in the opposite sides thereof adjacent the upper end, with aligned openings 19 through which the pin 15 and clamping bolt 17 may extend. The radiator sections are ordinarily provided
 10 with a second pair of aligned openings, adjacent their opposite ends, as shown at 20 in the drawing. In order to test the radiator sections for leaks, it is necessary to provide means for admitting fluid under pressure into
 15 the interior of the section through one of the openings and to seal the other openings so that the fluid cannot escape through them. The hollow flexible suspension members 9 communicate with the interior of the tubular
 20 frame member 5 and communication is established between the tubular suspension members and the interior of the radiator sections through a passage 22 formed in each of the clamping members 11 which are attached
 25 to the lower ends of the suspension members 9, an opening 23 being provided on the inner side of the jaw 11 which is adapted to register with an opening 19 of the radiator section to permit passage of fluid from the interior of
 30 the clamping jaw to the interior of the radiator section. Each clamping jaw 12 is provided with a sealing pad 21, upon the inner side thereof, which is clamped over the opening 19 in the side of the section with which
 35 it engages to seal said opening and the jaw 11 is provided, upon the inner side thereof, with an annular sealing pad 24 which surrounds the opening 23 and is clamped against the side of the radiator section to prevent
 40 leakage between the jaw and the radiator section.

A second clamp is provided for sealing the openings 20 at the lower end of each radiator section and this clamp consists of a pair of
 45 L-shaped jaws 25 and 26 one of which is provided with a laterally projecting pin 27 and the other of which is provided with a slot 28 through which the pin extends. The pin and slot connection permits the jaws to be moved toward and from each other and also to be swung about the pin 27 as a pivot. The pin 27 and slot 28 are carried by the shorter legs of the L-shaped jaws 25 and 26 and these shorter legs extend across, beneath
 55 the lower end of the radiator section when the clamp is secured to the section. The longer legs of the clamping jaws are adapted to extend up along opposite sides of the radiator section and have attached to the inner faces thereof sealing pads 29 and 30 which are adapted to be clamped over the openings 20 in the opposite sides of the radiator section, the clamp being held in place on the radiator section by means of a clamping bolt 31
 60 which extends through the jaws 25 and 26 and

through the aligned openings 20, in the radiator section.

In the operation of the device, a carrier with radiator sections to be tested is brought along the track 1 to the testing station where the inlet 6 of the tubular frame member may be connected with a water main. When the water enters the tubular member 5, it flows down through the flexible suspension members 9 into the radiator sections 18 to be tested and a leak in any one of the radiator sections will be at once detected. If there is an excessive leak in any radiator section, the flow of water thereto can be cut off by means of the valve 10 in the nipple 8 from which the leaking radiator section is suspended. The water flowing into the radiator sections displaces the air therein and to permit the escape of this air, the tubular frame member 5 is provided, upon the upper side thereof, with a valve controlled vent 32 which may be opened as the water is admitted into the frame member to allow escape of air while the radiator sections are being filled with water.

The flexible suspension for the individual radiator sections permits any section, in either row, to be swung outwardly and by giving the radiator section a quarter turn after it is swung clear of the adjacent sections, it may be supported in the position shown in dotted lines in Fig. 2, entirely outside the remaining sections, the width of the sections being such that when so turned, the side of the section which has been swung out, will bear against the edges of the two adjacent radiator sections to hold the section clear of the row of suspended radiator sections. A radiator section may thus be so supported as to render any portion thereof accessible for repairing a leak. The radiator sections, after they come from the molds, have rough edges or fins along the edges which are ordinarily chipped off before or after the testing and this operation can be conveniently performed on the radiator section by swinging them out one at a time and supporting them clear of the remaining sections. To facilitate operations on the sections at the testing station, a rigid partition wall 33 is provided to prevent the sections suspended from one side of the carrier from coming into contact with those suspended from the opposite side of the carrier. After the radiator sections have been tested and the desired finishing operations have been performed, the loaded carrier may be propelled along the overhead trackway 1 to the storage space or other unloading station.

Having thus described my invention, I claim:

1. In a device of the character described, a traveling carrier for hollow articles, said carrier having a hollow member provided with an inlet adapted to be detachably connected to a fluid conduit mounted independently of

the carrier, and means on the carrier for supporting a hollow article, said means also establishing communication between the interior of the hollow member and the interior 5 of a hollow article supported by the carrier.

2. In a device of the character described, a traveling carrier for hollow articles, said carrier having a hollow member provided with an inlet adapted to be detachably connected to a fluid conduit mounted independently of the carrier, and a hose connected at one end to said hollow member and having means at its opposite end for detachably securing the same to a hollow article, said 10 hose forming the means for supporting said article from said carrier.

3. In a device of the character described, a traveling carrier for hollow articles, said carrier having a hollow member provided 20 with an inlet adapted to be detachably connected to a fluid conduit mounted independently of the carrier, and a series of branch conduits connected at one end to said hollow member, each of said branch conduits having at its opposite end means for detachably connecting the same to one of the hollow articles, each of said branch conduits forming 25 the means for supporting said article from said carrier.

30 4. In a device of the character described, a traveling carrier for hollow articles, said carrier having a hollow member provided with an inlet adapted to be detachably connected to a fluid conduit mounted independently of the carrier, a series of branch conduits connected at one end of said hollow member, each of said branch conduits having at its opposite end means for detachably connecting the same to one of the hollow articles, 35 each of said branch conduits forming the means for supporting said article from said carrier and a valve for controlling the flow of fluid through each branch conduit.

5. In a device of the character described, 45 a carrier for hollow articles adapted to travel along an overhead trackway, said carrier having a fluid conduit adapted to be detachably connected with a fluid conduit mounted independently of the carrier, and means for connecting said first named conduit with the interior of a hollow article, said means supporting the hollow article.

6. In a device of the character described, 55 a carrier for hollow articles adapted to travel along an overhead trackway, said carrier having a fluid conduit adapted to be detachably connected with a fluid conduit mounted independently of the carrier, and means for connecting said first named conduit with the interior of a hollow article, to support the latter, said conduit being provided with a valve for cutting off the flow of fluid there-through.

7. In a device of the character described, 65 a carrier adapted to travel along an overhead

trackway and having a hollow frame member provided with means for connecting the interior thereof with fluid conducting means mounted independently of the carrier, and means for suspending a hollow article from 70 said frame member and for establishing communication between the interior of the frame member and the interior of the hollow article.

8. In a device of the character described, 75 a traveling carrier for hollow articles, said carrier having a hollow member provided with an inlet adapted to be detachably connected to a fluid conduit mounted independently of the carrier, a hose connected at one end to said hollow member and having means at its opposite end for detachably securing the same to a hollow article to establish communication between the interior thereof and the interior of the hollow member, and a valve 80 for controlling the flow of fluid through the 85 hose.

9. In a device of the character described, 90 a traveling carrier for hollow articles, said carrier having a hollow member provided with an inlet adapted to be detachably connected to a fluid conduit mounted independently of the carrier, and a hollow flexible suspension member attached at its upper end to the hollow frame member and communicating 95 with the interior thereof, said hollow flexible member having means at its lower end for supporting a hollow article and for establishing communication between the interior of said hollow article and the interior of the 100 hollow flexible member.

10. In a device of the character described, a carrier adapted to travel along an overhead trackway and having a tubular frame member provided with an inlet adapted to be connected to a fluid conduit mounted independently of the carrier, a series of hollow flexible suspension members attached to the frame member and communicating with the interior thereof, and means at the lower end of each suspension member for supporting a hollow article, said supporting means having a passage by which communication is established between the suspension member and the interior of the hollow articles. 105 110 115

11. In a device of the character described, a carrier adapted to travel along an overhead trackway and having a tubular frame member provided with an inlet adapted to be connected to a fluid conduit mounted independently of the carrier, a series of hollow flexible suspension members attached to the frame member and communicating with the interior thereof, means at the lower end of each suspension member for supporting a hollow article, said supporting means having a passage by which communication is established between the suspension member and the interior of the hollow article, and means for 120 125 130

cutting off the flow of fluid through any one of the suspension members.

12. In a device of the character described, a carrier adapted to travel along an overhead trackway and having a tubular frame member provided with an inlet adapted to be connected to a fluid conduit mounted independently of the carrier, a series of hollow flexible suspension members attached to the frame member and communicating with the interior thereof, and a pair of clamping members at the lower end of each suspension member between which a hollow article may be clamped, one of said clamping members having a passage establishing communication between the tubular suspension member and the interior of the hollow article.

13. In a device of the character described, a carrier adapted to travel along an overhead trackway and having a tubular frame member provided with an inlet adapted to be connected to a fluid conduit mounted independently of the carrier, a series of hollow flexible suspension members attached to the frame member and communicating with the interior thereof, a pair of clamping members at the lower end of each suspension member between which a hollow article may be clamped, one of said clamping members having a passage establishing communication between the tubular suspension member and the interior of the hollow article, and a valve controlling the flow through each of the suspension members.

14. In a device of the character described, a carrier adapted to travel along an overhead trackway and having a tubular frame member having longitudinally extending portions on opposite sides of the carrier and provided with an inlet adapted to be connected to a fluid conduit mounted independently of the carrier, a series of hollow flexible suspension members attached to each side portion of the frame member and communicating with the interior thereof, and means at the lower end of each suspension member for supporting a hollow article, said supporting means having a passage by which communication is established between the suspension member and the interior of the hollow article.

15. Testing apparatus comprising a traveling carrier for hollow articles to be tested, said carrier having thereon a conduit adapted to be detachably connected with a water main and with the interior of an article to be tested, and means for venting air from said conduit.

16. Testing apparatus comprising a carrier adapted to travel along an overhead trackway and having a tubular frame member provided with an inlet adapted to be detachably connected to a water main, a hollow flexible suspension member connected at its upper end to said frame member and in communication with the interior thereof, means

at the lower end of said suspension member for clamping a hollow article to be tested and for establishing communication between the interior of the hollow article and the interior of the suspension member, and means 70 for venting air from the interior of said hollow member.

17. Testing apparatus comprising a carrier adapted to travel along an overhead trackway and having a tubular frame member provided with an inlet adapted to be detachably connected to a water main, a hollow flexible suspension member connected at its upper end to said frame member and in communication with the interior thereof, means at the lower end of said suspension member for clamping a hollow article to be tested and for establishing communication between the interior of the hollow article and the interior of the suspension member, means for venting air from 80 the interior of said hollow member, and a valve controlling the flow of water through 85 the suspension member.

18. Apparatus for testing radiators comprising a carrier adapted to travel along an overhead trackway, said carrier having a tubular frame member extending longitudinally thereof, said tubular frame member having an inlet adapted to be detachably connected to a water main and a series of spaced nipples 95 projecting from the underside thereof, a flexible tube connected at its upper end to each nipple, and a clamp connected to the lower end of each flexible tube, said clamp having jaws adapted to engage opposite apertured 100 sides of a radiator section, one of said jaws being adapted to close the aperture in the side which it engages and the other jaw having a passageway therethrough communicating at one end with the tube and at its other with 105 the aperture in the radiator section.

19. Apparatus for testing radiators comprising a carrier adapted to travel along an overhead trackway, said carrier having a tubular frame member extending longitudinally thereof, said tubular frame member having an inlet adapted to be detachably connected to a water main and a series of spaced nipples projecting from the underside thereof, a flexible tube connected at its upper end to each nipple, a clamp connected to the lower end of each flexible tube, said clamp having 110 jaws adapted to engage opposite apertured sides of a radiator section, one of said jaws being adapted to close the aperture in the side which it engages and the other jaw having a passageway therethrough communicating at one end with the tube and at its other with 115 the aperture in the radiator section.

15. Testing apparatus comprising a carrier adapted to travel along an overhead trackway and having a tubular frame member provided with an inlet adapted to be detachably connected to a water main, a hollow flexible suspension member connected at its upper end to said frame member and in communication with the interior thereof, means 120 for venting air from said conduit having jaws adapted to engage opposite apertured sides of a radiator section, one of said jaws being adapted to close the aperture in the side which it engages and the other jaw having a passageway therethrough communicating at one end with the tube and at its other with the aperture in the radiator section, and a second clamp having jaws adapted to close 125 apertures in the sides of the radiator section adjacent its lower end.

In testimony whereof, I hereunto affix my signature.

EARL T. BENNINGTON.
